CRAFT PROPULSION

Horace M. Dobbins, Pasadena, Calif.

Application August 20, 1946, Serial No. 691,758

8 Claims. (Cl. 114—39)

1

This invention relates to rotary airfoils for propulsion and stabilization of water craft, ice boats and the like, and is more particularly directed to improvements in the mounting and controls of the rotors in such installations.

An object of the invention is the provision of a simple and efficient mounting for a rotor operatively disposed normally in a horizontal but capable of being moved at the will of the operator from the horizontal through various angles to said horizontal until the plane of the rotor is located vertically.

Another object of the invention is the provision of a rotor adjustably mounted on a mast for use as a gyroscopic element for aiding in stabilizing the craft when required.

A further object of the invention is a mounting for a rotor normally disposed in a horizontal plane, said mounting being slidable and tiltable on a mast erected in a craft, said mounting being rotatable through a predetermined angle around the mast and at the will of the operator.

Another object of the invention is to minimize the amount of gear and avoid the multiplicity of operative elements required to control the apparatus as well as to reduce hazards incident to the operation, the shifting of the rotor from a horizontal to a vertical, the rotation as well as the sliding of the mounting for the rotor being controlled by cables associated with a mast erected on a craft.

A still further object of the invention is the provision of a slidable and tiltable mounting for a rotor at the top of a mast in which an axle for the revolving rotor is carried outwardly from the vertical axis of the mast so that when the mounting is tilted, the rotor and mounting may be lowered to the deck of the craft when desired.

The invention consists in the novel construction, arrangement and combinations of parts hereinafter more particularly described and claimed.

In the drawings:

Figure 1 is a longitudinal view in elevation of a water craft equipped with my invention.

Figure 2 is a fragmentary view in elevation and partly in section of a mast showing the invention applied thereto, and

Figure 3 is a partial sectional view in elevation similar to the view shown in Figure 2, but at right angles thereto.

Referring more particularly to the drawings, 10 designates a water craft from which rises a mast 11. The upper free end 12 of said mast is round and through which is formed a groove 13. 55

2

The groove extends vertically downwardly at diametrically opposite points along the mast, as shown at 14 and 15 in Figures 2 and 3, and terminate adjacent the bottom of said mast.

5 A sleeve 20 is slidably mounted on the mast and has a pulley 21 attached to the lower end thereof. The upper end of said sleeve has an annular flange 22 which is adapted to engage diametrically disposed stops 23 projecting from the mast for limiting the upper movement of said sleeve.

A second sleeve 24 is also slidable on the mast but below the sleeve 20 with the upper end of the sleeve 24 normally in engagement with the under face of the pulley 21 attached to the lower end of the sleeve 20. A set screw 25 is threaded into an opening in the lower end of the sleeve 24 with the inner end of said screw disposed in the vertical groove 15 in the mast. Said screw is adapted to hold the sleeve 24 in a predetermined position along the mast.

A collar 30 is secured to the upper end of the sleeve 24 and is in normal engagement with the pulley 21. The collar has an extension 31. Grooved pulleys 32 are mounted on axles 33 projecting from the sides of the extension 31.

30 A cable 34 has one end secured at 35 to the upper end of the sleeve 24 (Fig. 2). A portion of the cable is located in the groove 14 of the mast and passes through an opening in the wall of the sleeve 24 where it is connected to said sleeve. The cable extends over the mast and is trained in the curved groove 13 and then downwardly in the groove 15. The lower free end of said cable emerges through a slot 36 formed in the sleeve 24 directly above the set screw 25. The lower end of the emerged cable is secured to a bolt or stay 37 (Figure 1).

40 A cable 40 is trained on the pulley 21, the pulleys 32 and a grooved pulley 41 (Figure 1) which is mounted on an axle 42 carried by the lower end of the mast 11. A hand wheel 43 is attached to the pulley 42 for rotating said pulley and operating the cable 40 to cause the sleeve 20 to rotate the mast, for a purpose which will be presently explained.

An elongated bracket 45 is secured to the exterior of the upper sleeve 20 and is located in a vertical plane. A head 46 is pivoted at 46—a in the upper end of the bracket and an axle 47 extends upwardly therefrom.

50 A channel bar 48 is disposed horizontally above the head 46 and has an opening through which the axle 47 passes. The channel bar at this point

is secured to the axle and the portion of said axle which is located in the channel bar is flat.

A brake drum 50 has a central passage which is received by the axle 47. The drum is seated on a washer 51 which rests on the bar 48.

A hub 52 of a rotor generally indicated by the numeral 53 which includes the airfoils 53-a, is rigid with the drum 50. A nut 54 threaded on the upper free end of the axle 47 holds the hub on said axle. A pin 55 retains the nut in place.

A brake band 56 of a conventional type has one end secured to a bar 57 which in turn is attached to one end of the channel bar 48. The other end of said band is connected by a link 58 to one end of a lever 59 pivoted intermediate its end at 60 on the forward end of the channel bar 48.

A cable 61 has one end secured to the other end of the lever 59 and is passed through an eye 62 mounted on one face of the bracket 45. The lower end of said cable is carried to a securing means 63 on the craft 10.

An arm 65 has one end inserted into the inner end 66 of the channel bar 48 where said end is pivoted at 67 to the channel bar. The outer free end of the arm is curved as shown at 68, so that when the channel bar 48 is tilted to the dotted line positions shown in Figure 1, the curved portion of the arm will pass freely over the top of the mast.

A cable 70 is attached to the free end of the curved portion 68 and then carried downwardly and secured to the stay 37. A cable 71 is connected between the forward end of the bar 48 and a cleat 72.

The operation of the apparatus is as follows: The rotor 53 and its support including the channel bar 48 are raised or lowered by the sleeves 20 and 24 when the portion of the cable 34 in the groove 15 is drawn downwardly or released. The rotor may be raised or lowered in any of the tilted positions shown in dotted lines in Figure 1. The set screw 25 aids in retaining the sleeve 24 in position.

The cable 70 when secured against slippage retains the channel bar 48 and the airfoils in horizontal position and thus the rotor in an operative position. When the cable is released the bar 48 and rotor will tilt or incline to the dotted line position shown in Figure 1 when the cable 71 is drawn downwardly.

The support for the rotor 53 including the bar 48 and the bracket 45 may be revolved around the mast by operating the hand wheel 43 in either direction. The cable 40 causes the grooved pulley 21 and the sleeve 20 to rotate when the wheel 43 is operated.

The set screw 25 riding in the groove 15 in the mast maintains the sleeve 24 against rotation.

With the rotor 53 shown horizontally in full lines in Figure 1, rotation of the rotor will have a gyroscopic effect tending to stabilize the craft 10. At this time the rotor will not act as a propulsion medium. However, varied propulsion may be obtained by changing the plane of rotation of the rotor from the horizontal to angular positions up to 90 degrees when the plane of rotation will be in a vertical plane.

Varied directional propulsion resultants may be developed by revolving the sleeve 20 on the mast 11 for changing the position of the axis of the axle 47 in an arc of a circle which has as its center the vertical axis of the mast 11 around which the axle, whether vertically disposed or at an angle to said vertical axis, travels.

When the sleeve 20 is rotated for varying the position of the axle 47 along a partial orbit, an adjustment must be made for the cable 61 controlling the brake band 56. No adjustment need be made for said cable when the rotor and its supporting elements are lowered unless it is desired to retain the rotor against rotation.

The cable or belt 40 will become slack when the sleeves 20 and 24 are lowered and the pulley 21 approaches the hand wheel 43. However, the set screw 25 riding in the groove 15 will hold the sleeve 24 against rotation.

The cables 70 and 71 will tend to become slack, likewise. These cables must be released to permit the rotor to move automatically from the horizontal plane to the vertical when the rotor is lowered by the manipulation of the cable 34 which maintains the sleeves in elevated positions. When the rotor is horizontally positioned, the channel bar 48 has its inner end 66 positioned directly over the top of the mast and rests thereon. The top of the mast forces the inner end of the channel bar upwardly when the rotor and the supporting elements are lowered.

In view of the fact that the rotor 53 must be of considerable length, in order to obtain the necessary sail area, it may be found desirable to have the airfoils 53-a of a foldable construction, and in order that this may be obtained, the aerofoils may be formed in two parts, hinged together as at 53-b and any suitable latch device 53-c being employed to hold the foil in rigid relation.

Although a preferred and practical embodiment of the invention is disclosed herein, it is to be understood that various modifications may be made that come within the scope of the appended claims.

I claim:

1. In an apparatus of the character described, a mast, a sleeve slidably mounted on said mast, a mounting for a rotor secured exteriorly to said sleeve and including a rockable head, an axle for the rotor projecting radially upward from the head, a horizontally disposed bar on the head and secured midway of its ends to the shaft and rockably with said head, said rotor being in a horizontal plane parallel to the bar and tiltable to various angles from the horizontal to a vertical plane parallel with the axis of the mast, means for retaining the rotor in a horizontal plane and causing tilting of said rotor, and means for sliding the sleeve and the mounting vertically along the mast.

2. In an apparatus of the character described, a mast, a rotor normally supported in a horizontal plane above said mast, a sleeve slidably mounted on the mast, a vertical axle for the rotor having the lower end rockably mounted on the exterior of the sleeve, means connected with the axle for adjustably positioning said axle at angles to the vertical and for tilting the rotor from the horizontal, and means for sliding the sleeve vertically on the mast when the rotor has been tilted to approximately a vertical plane.

3. In an apparatus of the character described, a mast, a rotor, normally supported in a horizontal plane above said mast, a sleeve slidably mounted on the mast, a vertical axle for the rotor having the lower end rockably mounted on the exterior of the sleeve, means connected with the axle for adjustably positioning said axle at angles to the vertical and for tilting the rotor from the horizontal, said sleeve having limited rotation on the mast, means for causing rotation of the sleeve for varying the angular position of

the axle in a semicircular orbit around the vertical axis of the mast, and means for sliding the sleeve vertically on the mast when the rotor has been tilted to approximately a vertical plane.

4. In an apparatus of the character described, a mast rising vertically from a craft, a sleeve rotatable and slidable on said mast, a vertically disposed bracket secured to the sleeve, a head rockably mounted in the upper end of the bracket, an axle rising vertically from the head, a horizontally disposed rotor on the axle, means for tilting the axle from the vertical to a horizontal position and for retaining said axle in various angular positions with respect to the vertical, and means for lowering the sleeve, axle and rotor when said axle is approximately in a horizontal position.

5. In an apparatus of the character described, a mast rising vertically from a craft, a sleeve rotatable and slidable on said mast, a vertically disposed bracket secured to the sleeve, a head rockably mounted in the upper end of the bracket, an axle rising vertically from the head, a horizontally disposed rotor on the axle, means for rotating the sleeve when the rotor is horizontally positioned for revolving the axle in a semi-circular orbit around the vertical axis of the mast, means for tilting the axle from the vertical to a horizontal and for retaining said axle in various angular positions with respect to the vertical, and means for lowering the sleeve, the axle and rotor when said axle is approximately in a horizontal position.

6. In an apparatus of the character described, a mast rising vertically from a craft, a sleeve slidably on the mast, a rotor mounting secured to the sleeve and including a vertical axle pivoted at one end on the sleeve and tilttable therefrom, a rotor on the axle and disposed normally in a horizontal plane above the mast, means controlling the tilting of said axle and for stabilizing the position of the axle and rotor, said mast having a groove in the top, said groove extending downwardly in the mast at diametrically opposite points, a second sleeve on the mast below the first sleeve, means carried by the last named

sleeve and projecting in the groove for preventing rotation of the sleeve, and a cable in the groove between the mast and the sleeves, one end of the cable having connection with the second sleeve, the other end of the cable having connections with the lower end of the mast so that when the last mentioned end is released the sleeve and rotor may be lowered.

7. In an apparatus of the character described, a mast rising vertically from a craft, a sleeve slidable on the mast, a rotor mounting secured to the sleeve and including a vertical axle pivoted at one end on the sleeve and tilttable therefrom, a rotor on the axle and disposed normally in a horizontal plane above the mast, means for controlling the tilting of said axle and for stabilizing the position of the axle and rotor, said mast having a groove in the top, said groove extending downwardly in the mast at diametrically opposite points, and a cable having connections with the sleeve, the other end of the cable having connections with the lower end of the mast so that when the last mentioned end is released the sleeve and rotor may be lowered.

8. In an apparatus of the character described, a mast, a sleeve adapted to be rotated on said mast, a grooved pulley secured to and embracing the sleeve, a vertical axle carried outwardly of and by the sleeve, a rotor on the axle and disposed in a horizontal plane above the mast, a cable trained on the pulley for rotating the pulley, and the sleeve on the mast and for revolving the axle in a semi-circular orbit about the vertical axis of the mast, and means for causing actuation of the cable.
